DESIGN FOR A CARVING AID

Vincent I. Mason, Newton, Mass., assignor to Boston Manufacturing Co., Boston, Mass., a partnership

Application February 6, 1947, Serial No. 136,733

Term of patent 7 years

(Cl. D44—29)

To all whom it may concern:

Be it known that I, Vincent I. Mason, a citizen of the United States of America, residing at Newton, in the county of Middlesex and Commonwealth of Massachusetts, have invented a new, original, and ornamental Design for a Carving Aid, of which the following is a specification, reference being had to the accompanying drawing, forming part thereof.

The drawing is a perspective view of a carving aid, showing my new design.

I claim:

The ornamental design for a carving aid, substantially as shown.

VINCENT I. MASON.
